UNITED STATES PATENT OFFICE.

JOHN S. THOMPSON, OF CHICAGO, ILLINOIS, ASSIGNOR TO MERGENTHALER LINOTYPE COMPANY, A CORPORATION OF NEW YORK.

LINOTYPE-MACHINE.

SPECIFICATION forming part of Letters Patent No. 732,383, dated June 30, 1903.

Application filed March 18, 1903. Serial No. 148,415. (No model.)

To all whom it may concern:

Be it known that I, JOHN S. THOMPSON, of Chicago, county of Cook, and State of Illinois, have invented a new and useful Improvement in Linotype-Machines, of which the following is a specification.

My invention has reference to linotype-machines—such, for example, as the ordinary Mergenthaler linotype—in which long slugs or line-printing bars are commonly used. It is frequently desirable to use these machines for producing slugs or forms for the printing of tabular matter, or matter having the figures or characters arranged in columns. 10 When the continuous slugs are cast, as usual, of the full width of the table, it is difficult to secure exact alinement of figures in the vertical columns and impossible to insert column-rules unless vertical slots are sawed 15 transversely through the slugs to receive them.

The aim of my invention is to provide simple means whereby the ordinary machines may be adapted to produce, instead of the 20 ordinary continuous slugs at one operation, a series of short slugs to be used end to end. In this manner I am enabled to bring the figures or characters on each slug in alinement vertically with the slug above and below it. 25 I am also enabled to introduce into a form composed of these lines of short slugs column-rules in the same manner that they would be inserted in an ordinary type-form. I accomplish the desired result by inserting in the 30 ordinary slotted mold adjustable partitions, whereby it is divided into a series of short lengths or sections adapted to form a corresponding series of short slugs of lengths 35 corresponding to the widths of the columns to appear in the table. In connection with this mold I employ special division-pieces, abutments, or quads, adapted to interlock with the partitions of the mold, so that they are 40 kept in exact alinement therewith and of 45 exactly the predetermined distances apart. The division-pieces thus secured against lateral movement determine the position of the intervening matrices and locate the figures on the face of the slug in exact positions required. The fixed division-pieces or quads

divide the matrices in the line into groups of definite width, each group representing the width of one column. When the figure-matrices are made of uniform width or in width multiples of a common unit, they will justify 55 to produce a compact line. When, however, matrices of different widths are used, so that the line needs justification, I propose to employ in the line adjacent to each of the matrices an ordinary expansible wedge spacer 60 of the Schuckers type, such as is commonly used in the linotype-machine. As these spacers require to be advanced independently to effect the justification of the respective groups of matrices, I employ a follower or 65 pressure device composed of a series of yielding sections, which will act one on each of the spacers.

Referring to the drawings, Figure 1 is an inside face view of the vise or line-supporting 70 mechanism of a linotype-machine containing a line of matrices and spacers in connection with my improved parts. Fig. 2 is a perspective view of the mold, showing the abutments or division-pieces therein and one of the interlocking matrices. Fig. 3 is a side view of one of the abutments or division-pieces. Fig. 4 is a perspective view of one of the mold-partitions. Fig. 5 is a side elevation showing the mold, the galley to receive the slugs, and the means 80 for delivering the slugs from the mold to the galley. Fig. 6 is a horizontal section on the line 6 6 of Fig. 5. Fig. 7 is a front view of the parts shown in the two preceding figures. Fig. 8 is a front or edge view of the series of 85 slugs, such as are produced in the mold at one operation.

Referring to the drawings, A represents the vise-frame, forming a portion of the main frame; B and C, the two opposing jaws in the 90 top of this frame for the purpose of confining the matrix-line endwise in the casting position and determining its length.

D represent ordinary figure or character matrices composed in the line.

E represent my division-pieces or abutments seated in the line and dividing the same into groups of four, five, or six, more or less, according to the number of vertical rows to appear in each column. These divi- 100

sion-pieces E are of the same external form as the ordinary character-matrices except that they are each provided with a protruding pin or stud e, as shown in Fig. 3. They 5 may be carried in the magazine and inserted in the line during its assemblage by the ordinary key mechanism or they may be inserted by hand.

F represents the slotted mold in which the 10 slug is cast, its face being held during the casting operation tightly against the matrix-line that it may be closed thereby as usual. The mold-slot extends through it, as usual, from the front to the back, and in the cap of 15 the mold there are a series of transverse grooves f.

I divide the mold by partition or division pieces G into a series of short lengths or sections corresponding in width to the group, or 20 sections in the matrix-line, so that when the mold is filled with molten metal it will produce, instead of the usual solid or continuous slug, a series of short slugs. When the mold is in position, each partition G will register 25 exactly with one of the division-pieces E in the line.

Cavities are formed in the front ends of the partitions to receive the studs e of the division-pieces. Owing to this interlocking 30 of the division-pieces E with the mold, the division-pieces are prevented from shifting laterally and are held exactly in the predetermined positions, so that they in turn fix exactly the positions of the intermediate 35 matrices D. It follows, therefore, that the series of short slugs cast at each operation will be precisely of the same length as those cast at the next operation and that the figures or other characters formed on one slug will 40 exactly align vertically with the slugs occurring above or below it in the form.

While I prefer to secure the partitions by forming them, as shown, with ribs seated in corresponding grooves in the mold-cap, it is 45 obvious that they may be varied in form and secured against lateral movement in any appropriate manner.

I propose to provide the mold with grooves f at short intervals, so that the partitions 50 may be adjusted laterally and arranged at any desired distance apart to suit the requirements of different tables, and of course the partitions may be made to extend to any desired distance on either side of their ribs, so 55 that there will be more or less space between one partition and the next, as occasion may require.

While I propose to employ the conical projections on the division-pieces to enter corresponding cavities in the partitions, it is manifest 60 that the interlocking surfaces of these two parts may be varied at will, provided only the partitions serve to hold the matrices securely against lateral movement.

65 For the purpose of delivering the series of slugs or linotypes from the mold after it has

been turned to the usual discharging position I employ, as shown in Fig. 5, ejector-slide H, having a series of narrow ejector-blades h, corresponding substantially in width 70 to the several chambers or sections of the mold. In order to support the series of slugs and hold them in line as they are delivered into the galley K in front of the mold, I provide a forwardly-yielding plate L, which 75 stands normally opposite the usual vibrating pusher M, which latter acts to push the slugs laterally into the galley. When the ejector advances, the series of short slugs are delivered between the plate L and the pusher M, 80 whereby they are maintained in position one above another and prevented from falling into a pile, as they would otherwise be liable to do. The plate L is mounted on a pivot l, so that it may swing forward away from the 85 slugs and out of their path when they are to be pushed laterally in the galley. A spring l² tends to hold the plate L in its operative position. As the pusher M advances toward the matrix-line a beveled lip m on its lower 90 portion acts with a lifting effect beneath a lip l³ on the plate L, near its pivot, the effect being to swing the plate L forward beyond the slugs and out of the path of the pusher.

It will be observed that the partitions G 95 are inserted from the front of the mold, so that they are held back to their places therein by the pressure of the division-pieces or abutments E against their forward ends. It will also be observed that the ribs of this partition terminate at a distance from the rear end, so that being seated in corresponding grooves it is impossible to push the partitions backward out of position.

In making use of my invention the operator 105 first determines the widths of the several columns which are to appear in the table. He then inserts the partition-plates G into the mold in the required positions to produce short slugs of the requisite length.

110 In assembling the line of matrices the special division-pieces or abutments are inserted at distances apart corresponding to those between the mold-partitions. The machine is then operated in the ordinary manner. When 115 the matrix-line is presented to the mold, the studs of the division-pieces interlock with the partitions in the mold. If the line is not already justified, the expandable spacers N, which are inserted adjacent to the division- 120 pieces, are thrust upward, each being subjected to pressure independently of the others, whereby small groups of matrices are justified independently and in one direction 125 between the division-plates or abutments. The ejector acting in due time drives the entire series of slugs out of the mold and alongside of the plate L. This plate is in due time refracted, the line pushed forward horizontally in the galley by the follower M, and 130 the plate L returned to its operative position to maintain the vertical alignment of the se-

ries of slugs when the pusher retreats preparatory to the delivery of the next line into the galley.

Having thus described my invention, what I claim is—

- 5 1. In a linotype-machine, a slotted mold divided by a series of fixed partitions, that it may produce a series of short slugs, in combination with a series of division-pieces or 10 abutments adapted to interlock with the mold-partitions, whereby they are secured against lateral movement, and adapted to determine the position of the intervening matrices.
- 15 2. In a linotype-machine, the mold, a transverse partition inserted from the front and a division-piece or abutment arranged to act against the forward end of the partition, whereby it is held to its place in the mold.
- 20 3. In a linotype-machine, the mold having a partition G, with a cavity therein, in combination with a division-piece or abutment E, having a projection to enter said cavity.
- 25 4. In a linotype-machine, a mold provided with a laterally-adjustable partition G, in combination with a division-piece or abutment adapted to interlock with the said partition.
- 30 5. In a linotype-machine, a mold adapted to form a series of slugs, means for ejecting the slug endwise from the mold, a galley, and means for supporting the outgoing slugs, and maintaining them in line as they enter the galley.
- 35 6. In a linotype-machine, a mold adapted to form a series of slugs, an ejector for delivering the slugs endwise, and a galley to receive them, in combination with two plates or sup-

porting-surfaces between which the slugs are received.

7. In a linotype-machine producing a series of short slugs at each operation, a receiving galley, means for delivering the slugs endwise from the mold to the galley, a plate L, a pusher M, and means for retracting the plate L, after the delivery of the slugs to the galley.

8. In a linotype-machine, the combination of a mold divided by a partition that it may produce a plurality of slugs, a line of matrices, means for confining the line endwise in front of the mold, a division-piece or abutment E, inserted in the line, dividing the same into groups or sections, and arranged to interlock with the partitions of the mold, expansible spacers seated one in each section of the line, and means for advancing said spacers independently of each other.

9. In a line-casting machine, and in combination with a composed line of matrices, a mold divided by partitions that it may produce a plurality of short slugs, division-pieces or abutments E, inserted in the matrix-line and interlocking with the partitions, and independently-operated expansible spacers inserted in the line, one adjacent to each of the division-pieces or abutments.

In testimony whereof I hereunto set my hand, this 6th day of March, 1903, in the presence of two attesting witnesses.

JOHN S. THOMPSON.
